UNITED STATES PATENT OFFICE

2,599,134

CLOTHESLINE STRETCHER

Roland R. Scofield, Niles, Mich.

Application September 25, 1946, Serial No. 699,288

1 Claim. (Cl. 211—119.15)

1

This invention relates to new and useful improvements in clothes line tighteners and fasteners and more particularly to a device which is attached to the end of a clothes line to facilitate the stretching of the line and retaining said line in a taut condition.

A further feature of the invention is to provide a clothes line stretcher of the class described which is simple and durable in construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a rear elevational view of the invention in a locked position showing the stretcher secured to a support and with the line attached thereto;

Figure 2 is an enlarged top plan view of the device, the vertical drum removed;

Figure 3 is an enlarged side elevational view of the device with the line supporting bar shown in section;

Figure 4 is a similar view of the device in a locked position;

Figure 5 is a perspective view of the vertical drum, and

Figure 6 is a perspective view of the locking handle.

Referring now to the drawing in detail, wherein for the purpose of illustration, I have disclosed a preferred embodiment of the invention, the numeral 5 represents a flat L-shaped handle having a square opening 6 at one end and a laterally curved locking arm 7 extending from one side edge of the handle. A circular drum 8 has a squared end 9 adapted to enter the opening 6 so that the drum is at right angles to the handle. The free end of a clothes line 10 is extended through an opening 11 in a horizontal clothes line supporting bar 12 and said line is extended through a transverse opening 13 in substantially the center of the drum. The handle is then attached to the squared lower end of the drum with the locking arm extending downwardly, as shown in Figure 3. A knot (not shown) may be tied in the free end of the line to rest against the drum. As the handle is rotated horizontally the drum is likewise rotated and the clothes line becomes wound thereon. The handle is then removed from the drum and reversed so that the locking arm is extended upwardly and against the clothes line bar as shown

in Figure 4, to thus secure the drum against unwinding movement.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

What I claim as my invention is:

A device for tensioning a line between a tubular line support and a point remote therefrom and comprising a cylindrical drum having a transverse opening adapted for anchoring a line thereto for winding on the drum, said support having a transverse opening through which the line is slidably and said line manually rotatably holding the drum at right angles to the axis of the support, a handle constructed of strap metal and detachably connected at one end to the drum, and an arcuate crank arm projecting laterally at one edge of the handle outwardly with respect to the attached end of the drum when the handle is placed thereon in one position and said crank arm projecting inwardly with respect to the attached end of the drum to partially embrace the support and lock the drum from rotation in a predetermined direction when the handle is reversed on the drum.

ROLAND R. SCOFIELD.
